(57) **CLAIM**

The ornamental design for a veterinary orthopedic brace for elbow, as shown and described.

DESCRIPTION

FIG. 1 is a left side elevation view of a veterinary orthopedic brace for elbow, showing our new design;

FIG. 2 is a right side elevation view thereof;

FIG. 3 is a left side view shown within an environment of use;

FIG. 4 is a rear view thereof;

FIG. 5 is a right side view thereof;

FIG. 6 is a front view thereof;

FIG. 7 is a top plan view of the article as shown in FIG. 1; and,

FIG. 8 is a bottom plan view thereof.

The evenly spaced broken lines depict portions of the article that form no part of the claimed design. The long dash-short dash broken lines depict environmental subject matter that forms no part of the claimed design.

1 Claim, 8 Drawing Sheets
